UNITED STATES PATENT OFFICE.

JAMES B. GIVEN, OF CHICAGO, ILLINOIS.

COIN-HOLDER.

1,126,192.

Specification of Letters Patent.

Patented Jan. 26, 1915.

Application filed July 30, 1913, Serial No. 782,103. Renewed June 25, 1914. Serial No. 847,335.

To all whom it may concern:

Be it known that I, JAMES B. GIVEN, a citizen of the United States, residing at Chicago, in the county of Cook and State of Illinois, have invented certain new and useful Improvements in Coin-Holders, of which the following is a specification.

This invention is a coin holder in the form of a book, the leaves thereof having pockets 10 into which the coins are inserted, said pockets being dimensioned to hold a single coin.

It is the object of the invention to provide a novel and improved coin holder of this kind, and to this end it consists in a combination and arrangement of parts to be hereinafter described and claimed, reference being had to the accompanying drawing in which—

Figure 1 is a perspective view of the book, 20 partly open; and Fig. 2 is a detail showing a leaf of the book in section, with a coin in place in one of the pockets.

Referring specifically to the drawing the book is made up of leaves, and front and 25 back covers 5 and 6 respectively. Each leaf is provided with a series of coin pockets each of which is dimensioned to hold a single coin. The pockets are arranged in parallel rows extending across the leaves. At the 30 head of each leaf is a space for filling in the month of the year when the coins are deposited in the pockets. Each pocket is also numbered, said numbers being arranged in consecutive order across the leaves, and designating the days of the month. The pockets 35 at the bottom of the leaves are designated "Extra" and are for the purpose of receiving extra deposits. The size of the leaves is such that each side has eighteen 40 pockets, thus allowing fifteen pockets numbered "1" to "15" and three "extra" pockets on one side, and sixteen pockets numbered "16" to "31" and two "extra" pockets on the other side. It is not necessary to 45 vary this arrangement for the months having less than thirty days.

The pockets are formed by pasting over a sheet 7 of stiff paper, on each side thereof, a sheet 8 of thin paper having transverse and 50 parallel rows of slits 9, the slits in each row being spaced from each other and of uniform length. The outside sheets are not pasted over the entire surface of the inner

sheet, but the adhesive is applied only along the edges and in rows running vertically and 55 transversely, as shown by dotted lines in Fig. 1. The portions of the outside sheets which are between the rows of adhesive are therefore not stuck to the inner sheet, whereby the coin pockets are formed, the slits 9 60 being correspondingly arranged to form the entrance of the pockets.

The book is designed to hold coins of the same denomination. In the present instance the pockets are dimensioned to hold dimes. 65 For coins of other denominations a book having correspondingly dimensioned pockets will be provided. The manner in which the pockets are numbered to correspond to the days of the month may be varied in many 70 ways and the invention is not limited to the precise arrangement shown.

The invention is designed primarily to serve as an advertising proposition for savings banks and to foster regularity in saving a certain amount every day. 75 When the book is filled, it is to be taken to the bank for deposit of the coins it contains.

The loose portions of the outer sheets 8 fit tightly over the coins and hold the same 80 firmly in place. This prevents removal of the coins after they are placed in the pockets without mutilating the book.

I claim:

1. A coin holder in the form of a book 85 having leaves, and front and back covers, and sheets gummed to the leaves and having rows of spaced slits, the gummed portions of the sheets extending in rows running vertically and transversely and the portions of 90 the sheets between said rows of perforations being loose and forming coin pockets, the aforesaid slits coinciding with the pockets and forming the entrance thereof.

2. A coin holder in the form of a book 95 having leaves, and front and back covers, and sheets gummed to the leaves and having rows of spaced slits, the gummed portions of the sheets extending in rows running vertically and transversely and the portions of 100 the sheets between said rows of perforations being loose and forming coin pockets, the aforesaid slits coinciding with the pockets and forming the entrance thereof, said pockets being numbered to correspond to the 105 days of the month.

3. A coin holder comprising a plurality of leaves assembled in the form of a book, and sheets associated with the leaves and having portions fastened thereto leaving loose portions to form coin pockets, said sheets having slits coinciding with the pockets and forming the entrance thereof.

In testimony whereof I affix my signature in presence of two witnesses.

JAMES B. GIVEN.
